UNITED STATES PATENT OFFICE.

EDWARD W. NEWELL, OF PITTSBURGH, PENNSYLVANIA, ASSIGNOR TO THE
WESTINGHOUSE AIR BRAKE COMPANY, OF WILMERDING, PENNSYLVANIA, A
CORPORATION OF PENNSYLVANIA.

PROJECTILE TIME-FUSE.

1,309,771.

Specification of Letters Patent. Patented July 15, 1919.

Application filed June 23, 1917. Serial No. 176,604.

To all whom it may concern:

Be it known that I, EDWARD W. NEWELL, a citizen of the United States, residing at Pittsburgh, in the county of Allegheny and 5 State of Pennsylvania, have invented new and useful Improvements in Projectile Time-Fuses, of which the following is a specification.

This invention relates to projectiles, and 10 more particularly to a time fuse mechanism.

The principal object of my invention is to provide a time fuse mechanism adapted to be controlled by means of a generated gas.

Other objects and advantages will appear 15 in the following more detailed description of the invention.

In the accompanying drawing; Figure 1 is a central sectional view of a time fuse mechanism embodying my invention, and 20 showing the parts in normal position; Fig. 2 a similar view, showing the parts in positions assumed upon firing the projectile from the gun; Fig. 3 a similar view, showing the positions of the parts after the fuse 25 mechanism has operated to explode the projectile; Fig. 4 a sectional view of a portion of the fuse mechanism, showing the positions of the parts as assumed in case the projectile strikes an object before the time 30 fuse operates; Fig. 5 a transverse section on the line *a—a* of Fig. 1; Fig. 6 a rear face view of a portion of the adjustable vent ring; and Fig. 7 an elevational view, partly 35 in section, of the nose portion of the fuse mechanism.

As shown in the drawing, the construction 40 may comprise a member 1 adapted to be screwed into the main casing of the projectile and having screw threaded engagement with said member is a fuse casing 2.

A sleeve 3 is screwed into the rear end of member 1 and a longitudinally movable primer holder 4 containing a primer 5 normally engages an annular shoulder of the 45 sleeve.

Slidably mounted in a sleeve extension 6 of the member 1 is a firing plunger 7 adapted upon movement to engage the primer 5.

Normally engaging a forward annular 50 shoulder 8 of sleeve 6 is a spring clip 9 and interposed between said clip and the firing plunger 7 is a coil spring 10.

A piston 11, subject on one side to the pressure in a chamber 12, is mounted in the

fuse casing 2 and a spring 13 acts on the 55 opposite side of the piston.

On the extension 6 is slidably mounted a sleeve 14, engaged at the forward end by spring 13 and having a rear conical face 15 adapted to be engaged by conical heads 60 of radially movable pins 16 mounted in the extension 6, said pins having inwardly extending conical points, adapted to engage within a V shaped annular groove 17 of the firing plunger 7.

Screwed into the spring clip 9 is a rod 18 having the rear portion split to form flared prongs 19 having the rear ends inclined to engage corresponding inclined surfaces on the primer holder 4.

Screwed onto a forward threaded extension 20 of the casing 2 is a nose member 21 having a central rearwardly extending sleeve 22 into which is screwed an auxiliary primer holder 23 containing a primer 24 75 and mounted in a central bore of the sleeve 22 in an auxiliary firing plunger 25.

An annular chamber 26 surrounds the sleeve 22 and is adapted to contain a cartridge 27 formed of a substance which will 80 generate gas when ignited.

The piston 11 is provided with a forwardly extending stem 28 which is normally secured to the nose member 21 by a small screw 29, so as to prevent movement 85 of the piston by accidental jarring of the projectile, the stem 28 being also adapted to prevent rearward movement of the auxiliary firing plunger 25.

Engaging a vertical face of the casing 2 90 is a rotatable ring 30 having a series of orifices 31 of varying sizes which open at one side to passages 32 of uniform size and at the opposite side to a groove 33 formed in a clamping ring 34 which is adapted to 95 be screwed onto the sleeve 20 for clamping the ring 30 in its adjusted position. At one point in the circumference of the ring 30 there is provided an atmospheric vent port 35, adapted to constantly register with 100 the groove 33.

A passage 36 adapted to register with the passage 32 opens into chamber 12 and in order to hold the ring 30 in its adjusted position, a pin 37 is secured in the casing 2 105 so as to register with one of the passages 32, as shown in Fig. 7 of the drawing.

A gasket 38 of soft material may be inter-

posed between the ring 30 and the casing 2, in order to facilitate the making of a tight joint therebetween.

In operation, the parts are normally in the positions shown in Fig. 1 of the drawing, with the spring clip 9 held against shoulder 8 by spring 10 and the primer holder 4 prevented from forward movement by the prongs 19 of stem 18.

10 The piston 11 is maintained in its forward position by the screw 29 and stem 28 prevents the rearward movement of firing plunger 25.

When it is desired to fire the projectile, 15 the clamping ring 34 is backed off, and the ring 30 is moved forward so as to clear the pin 37 and then the ring 30 is rotated to bring one of the orifices 31 into registry through passage 32 with passage 36, the orifices 31 being of a calculated area such that 20 the fluid within chamber 12 will escape in a predetermined period of time, as indicated by graduations (not shown) on the periphery of ring 30.

25 The ring 30 is then moved back, so that the pin 37 engages in a registering passage 32 of the ring and the clamping ring 34 is screwed home.

Upon firing the projectile from the gun, 30 the piston 11 is thrown rearwardly by inertia, stripping the threads of the screw 29 and compressing the spring 13 against the ring 14. In its rearward movement, the piston 11 engages the spring clip 9 and moves 35 same rearwardly, compressing the spring 10 against the firing plunger 7, and finally, the bent ends of the clip pass a shoulder 39 of the sleeve extension 6 and fly outward, so as to prevent any forward movement of the 40 clip, and thus hold the spring 10 under compression.

The rearward movement of stem 18 with clip 9 causes the prongs 19 to collapse, so as to permit their passage through the opening 45 in the primer holder 4 to the position shown in Fig. 2 of the drawing.

The pressure exerted by the heavy spring 13 against the pins 16 is sufficient to prevent the outward radial movement of the pins by 50 the pressure of spring 10 which also acts on the pins through the firing plunger 7.

The inertia of the auxiliary firing plunger 25 causes a relative rearward movement of same, the stem 28 having been moved 55 rearwardly, so that the firing plunger engages the auxiliary primer 24 which is then detonated, and acts to ignite the cartridge 27. This causes the generation of gas which 60 fills the chamber 12 at a predetermined pressure, the composition and size of the cartridge being calculated, so as to produce the necessary volume of gas.

This gas pressure acts in chamber 14 to hold the piston 11 at its rearward position 65 against the counter resistance of spring 13,

but during the flight of the projectile, the gas in chamber 12 escapes through the orifice 31 which is in communication through passage 32 with passage 36, the gas flowing thence through groove 33 to atmospheric exhaust passage 35.

When the pressure in chamber 12 has been reduced to a predetermined degree, the piston 11 moves forward and relieves the spring pressure exerted by spring 13 on ring 14 70 and finally, the pressure of spring 10 preponderates sufficiently to force the pins 16 radially outward and thus permit the firing plunger 7 to move rearwardly and engage the primer 5 as shown in Fig. 3 of the drawing, 80 thus detonating the projectile.

If for any reason, the timing mechanism above described should fail to act during the flight of the projectile, then upon the projectile striking an object or grazing an object 85 in flight, the inertia of the primer holder 4 causes its relative forward movement, forcing the split spring ring 40 outwardly so that the same will engage the firing plunger 7, as shown in Fig. 4 of the drawing, 90 and thus cause the explosion of the projectile.

Having now described my invention, what I claim as new and desire to secure by Letters Patent, is:—

95

1. In a projectile, the combination with a chamber having a vent port and a time fuse mechanism operated according to the pressure in said chamber, of a gas forming substance and means operated upon firing the 10 projectile for effecting the generation of gas from said substance to thereby create a fluid pressure in said chamber.

2. In a projectile, the combination with a chamber having a vent port open to the atmosphere and a time fuse mechanism operated upon a reduction in pressure in said chamber, of means in the projectile for generating and initially charging said chamber with fluid under pressure.

3. In a time fuse mechanism, the combination with a firing plunger and a chamber having an atmospheric exhaust port, of a piston device controlled by the pressure in said chamber for controlling the operation 1 of the firing plunger and means for generating gas to produce an initial fluid pressure in said chamber.

4. In a projectile, the combination with a chamber, a firing plunger, and a piston subject to the pressure in said chamber and operated upon a predetermined reduction in pressure in said chamber for effecting the operation of said firing plunger, of a substance adapted upon ignition to form a gas in said chamber and means operated upon firing the projectile from the gun for igniting said substance.

5. In a projectile, the combination with a chamber having an atmospheric exhaust

- port, a firing plunger, and a piston subject to the pressure in said chamber for controlling said plunger, of a gas forming charge and an auxiliary firing plunger operated 5 upon firing the projectile from the gun for effecting the ignition of said charge to form gas under pressure in said chamber.
6. In a projectile, the combination with a chamber having an atmospheric exhaust 10 port, a main firing plunger, and a piston subject to the pressure in said chamber for controlling said plunger, of a gas forming charge, a primer, and an auxiliary firing plunger operated by inertia upon firing the 15 projectile from the gun for detonating said primer to effect the ignition of said charge and the generation of gas in the chamber.
7. In a projectile, the combination with a main firing plunger, a chamber, and a piston 20 subject to the pressure in said chamber for controlling said plunger, of a cartridge composed of a gas forming substance and communicating with said chamber, a primer adapted upon detonation for igniting said 25 cartridge, and an auxiliary firing plunger operated by inertia upon firing the projectile from the gun for detonating said primer.
8. In a projectile, the combination with a main firing plunger, a chamber, and a piston 30 subject to the pressure in said chamber for controlling said plunger, of means operated upon firing the projectile from the gun for generating gas in said chamber and means for venting gas from said chamber at a pre- 35 determined rate.
9. In a projectile, the combination with a main firing plunger, a chamber, and a pis- ton subject to the pressure in said chamber for controlling said plunger, of a substance adapted upon ignition to generate gas in said chamber, an auxiliary firing plunger for effecting the ignition of said substance, and means carried by said piston for normally preventing the movement of said auxiliary firing plunger. 45
10. In a projectile, the combination with a main firing plunger, a chamber, and a piston subject to the pressure in said chamber for controlling said plunger, of a substance adapted upon ignition to generate gas in 50 said chamber, an auxiliary firing plunger for effecting the ignition of said substance, means for normally preventing movement of said piston, and means carried by said piston for normally preventing movement of 55 said auxiliary firing plunger.
11. In a projectile, the combination with a main firing plunger, a chamber, and a piston subject to the pressure in said chamber for controlling said plunger, of a substance 60 adapted upon ignition to generate gas in said chamber, an auxiliary firing plunger for effecting the ignition of said substance, a stem carried by said piston for normally preventing movement of said auxiliary 65 plunger, and a screw for normally preventing movement of the piston and adapted to be stripped from its screw threaded engagement with the piston by movement of the piston through inertia upon firing the projectile from the gun. 70

In testimony whereof I have hereunto set my hand.

EDWARD W. NEWELL.
